(57) **CLAIM**

The ornamental design for a charging case with earphone, as shown and described.

DESCRIPTION

1. Charging case with earphone

1.1 : Perspective view of a charging case with earphones

1.2 : Perspective view of the charging case in closed position

1.3 : Front view of the charging case in closed position

1.4 : Back view of the charging case in closed position

1.5 : Left view of the charging case in closed position

1.6 : Top view of the charging case in closed position

1.7 : Bottom view of the charging case in closed position

1.8 : Perspective view of the earphone

1.9 : Perspective view of the earphone

1.10 : Front view of the earphone

1.11 : Back view of the earphone

1.12 : Left view of the earphone

1.13 : Right view of the earphone

1.14 : Top view of the earphone

1.15 : Bottom view of the earphone

The parts shown by means of broken lines in the reproductions are not part of the claimed design; right view of the charging case in closed position is omitted because it is a mirror image of the left side view.
